DESIGN.

—o—

H. HUNT.

CARPET.

No. 17,646.

Patented Aug. 23, 1887.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 17,646, dated August 23, 1887.

Application filed July 21, 1887. Serial No. 244,940. Term of patent 3½ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

15 My design consists of several large clusters

or groups of leaves or flowers thickly massed together, the groups or clusters being irregularly disposed over the face of the carpet. In the intervals between the figures is a stem-work supporting long curving leaves, together 20 with a few smaller flowers and leaves.

What I claim as new, and desire to secure by Letters Patent, is—

The design for carpets, consisting of the design substantially as shown.

HENRY HUNT.
